(57) **CLAIM**

The ornamental design for a portable moisture tester, as shown and described.

DESCRIPTION

The present design is drawn to a portable measuring instrument for measuring the moisture content of grain materials. FIG. 1 is a top perspective view of the new design moisture tester;

FIG. 2 is a full front view of the new design moisture tester; FIG. 3 is a full right side view of the new design moisture tester;

FIG. 4 is a full top view of the new design moisture tester; FIG. 5 is a full rear view of the new design moisture tester;

FIG. 6 is a full left side view of the new design moisture tester; and,

FIG. 7 is a full bottom view of the new design moisture tester.
